INTAKE FUEL SYSTEM FOR INTERNAL-COMBUSTION ENGINES

Ora F. Haibe, Indianapolis, Ind.

Application March 12, 1943, Serial No. 478,855

7 Claims. (Cl. 48—180)

This invention relates to improvements in the intake fuel system of internal combustion engines and is more specifically directed to improvements upon the structure illustrated, described and claimed in the prior Patent No. 2,292,071, dated August 4, 1942.

Under present national speed regulations and tire conservation efforts (enforced through gasoline rationing) it is not as critical to develop maximum power at the top speed of which the vehicle is capable and for which the intake system has been initially designed.

For a complete understanding of the present invention, reference is particularly had to the aforesaid patent, which disclosure is specifically made a part hereof. Also as described and claimed therein, the invention herein is not of necessity restricted to the so-called adapter or insert form, but may be built into the carburetor downstream of the throttle valve thereof, or in the intake manifold upstream of the distributing portion of the latter.

The chief object of the present invention is to obtain more miles per gallon of gasoline or liquid fuel of vaporizable type and also to improve both performance and particularly economy when accelerating.

The chief feature of the present invention is the inclusion of an imperforate web-like arrangement between the rib grooves of the patented structure, which web-like arrangement is localized at two opposite sides of the intake passage and is of substantially greatest radial width substantially transverse to the axis of the carburetor throttle valve shaft, the webbing in the preferred form being discontinuous or of zero radial width in alignment with the axis of the carburetor throttle valve and immediately adjacent such aforementioned locations which are on opposite sides of the intake passage and midway between the maximum radial width portions of the webbing.

Other objects and features of the invention will be set forth more fully hereinafter.

The full nature of the invention will be understood from the accompanying drawing and the following description and claims:

In the drawing

Fig. 1 is a vertical central sectional view of a down-draft intake system of an internal combination at the carburetor-manifold connection and with the invention interposed therebetween as an adapter insert, the pertinent portions of the carburetor (except the fuel pump operable upon acceleration) and the manifold only being

illustrated, and a portion of the latter is shown in elevation.

Fig. 2 is a top plan view of an adapter or insert plate form of the invention.

Fig. 3 is a transverse sectional view thereof taken on line 3—3 of Fig. 2 and in the direction of the arrows.

Fig. 4 is a transverse sectional view of the down-draft intake system and is taken immediately above or upstream of the carburetor throttle valve therein, the latter being shown about three-quarters closed or one-fourth open.

Fig. 5 is a vertical sectional view through an intake mounted cup form of adapter embodying the invention.

In view of the complete illustration and description set forth in the aforementioned patent, only the salient features of the present invention will be set forth and for convenience numerals similar to those utilized in said patent are employed herein to designate similar or like parts.

In the drawing 10 indicates a portion of a conventional down-draft carburetor wherein the intake passage widens out as at 13 from a Venturi formation not shown. Therebeneath and in said passage 27 is the balanced butterfly type throttle valve 14 carried by shaft 14a operable by the usual manually operable means. The outlet of the carburetor intake passage matches with the intake end of the intake passage 17 of the intake manifold 18. The carburetor outlet end is provided with flange 15 for connection as by members 16 for connection to said manifold.

As indicated at 29 the fuel mixture leaves the Venturi portion in a full cone-like formation. Included in this mixture is the combustible vapor and unvaporized fuel droplets 30.

The action of the throttle butterfly valve is illustrated clearly in Fig. 1 showing the deflecting characteristics of this valve and whereby only a minor portion of the vapor, when the valve is not fully opened, passes between the upper end of the valve and the intake passage, as indicated generally at A. The larger portion of the fuel mixture is deflected and concentrated and passes beyond that valve as indicated at B. Such liquid fuel as is intercepted by this valve is deflected toward the lower end of the valve and toward the carburetor intake wall immediately contiguous thereto. The completely vaporized fuel is thereupon uniformly distributed in the intake 17 by means of the invention now to be described more specifically, reference being had to Figs. 2 and 3.

In these figures, it is noted the invention is illustrated as of plate construction and of the adapter insert type. It includes a body portion 40 and the same is enlarged as at 41 to match the flange contour of the carburetor and intake manifold. It includes holes 42 therethrough adapted to permit passage of connecting bolts 16, so that when those bolts are tightened down, the invention is included in the carbureting system, included between the connecting flanges and with the insert therebetween are the gaskets G.

The body portion 40 is provided with a "central" opening 43 defined by a groove 44. The exterior diameter of the groove is approximately that of the intake passageway. The hole 43, therefore, is slightly smaller. Extending medianly in the present form of the invention and across the opening 43 is a grooved rib arrangement, the same being longitudinally aligned with the centers of the opening 42. This groove arrangement 45 communicates at opposite ends with the groove 44.

At each side of the central groove rib 45 is a second rib 46 and as shown clearly in the several figures, these ribs are preferably non-parallel to each other and non-parallel to the central rib 45. They are directed toward each other and the angle of inclination is approximately 8°. The limits of inclination are obtained between 5° and 10°, the 8° inclination being preferred in most instances since it insures the best performance.

It will be noted as a result of this inclination that a considerable amount of rib obstruction is positioned in alignment with the downstream side of the deflecting valve arrangement, so that maximum trapping of liquid fuel there will be effected. Each of the ribs, as previously stated, communicates at opposite ends with the opening defining wall groove 44. These ribs are of greater depth insofar as their grooves are concerned, than the wall defining groove and rib 45 has the deepest groove as shown in Fig. 3.

In longitudinal section, these ribs preferably are bowed so that the deepest portion is approximately at the central portion of the rib. Between the junction of the rib with the opening defining groove, each grooved rib is pierced with a minute or capillary type hole which preferably is left with a ragged or raw edge and this is on the downstream side or convex side of the grooved rib. The air or fuel mixture passing through the opening 43 creates on the underface of these grooved ribs a high vacuum or pressure depression which draws the collected liquid fuel on these ribs at this lower portion outwardly through the minute holes.

The ragged or raw edge defining said holes in addition to this vaporization incident to this vacuum action, seems to have the effect of tearing the liquid gasoline into still further minute portions so that what liquid is discharged from these grooves through these holes indicated by the numeral 50 is fully vaporized, and these holes constitute one source of relief or discharge for such liquid which is trapped by any or all of the groove arrangements. Herein three of these holes are shown in each rib, although a greater or lesser number may be provided and longer ribs may have more holes than shorter ribs.

It is to be noted also that the several rib arrangements constitute means for creating turbulence and, of course, with a minimum amount of interference to fuel mixture flow, and this high turbulence provides better distribution of

the fuel and air and serves to insure uniform distribution in the manifold.

For the purposes initially set forth herein there is included at each end of the ribs a lunar segment-like web arrangement having end portions 60 and rib intermediate portions 61. The extent of each segment is about 160° and when the throttle valve is about one-quarter open the projected area of the balanced elliptical valve is approximately coincident with the inner edges of the webbing, see Fig. 4.

The webbing may be slightly dished or inclined so that it may feed trapped fuel into the several adjacent grooves. High velocity mixture through the intake, that is high vacuum therein, results in part of this web trapped fuel being drawn over the segment edge and vaporized so it is included in the fuel mixture. This is in addition to the vaporization from apertures 50. This edge is indicated by the subscript a. The inner edges of each lunar segment is scallop-like and the segment adjacent the constructed ends of the ribs preferably is of greater radial width.

Accordingly at part throttle, below half throttle, the turbulence creating effect of said webbing and the globule trapping effect thereof is, upon acceleration, of proportionally greater effect, for it is at this time that the system is over-supplied with liquid fuel relative to the engine requirements and vaporization by the carburetor is the poorest.

At wide open throttle positions the aforesaid effects of the webbing, while still inherently always present and effecting economy and desired engine performance, are proportionately less relative to total effect, etc.

For proof of the aforesaid it is stated that intakes equipped with the patented insert showed clean and bright below the valve shaft and progressively cloudy at wall portions proportionately removed therefrom until at 90° or midway therebetween a decided smudge on the wall was observed.

The present invention when substituted for the patented invention showed a wall clean and bright entirely around same, which visually substantiated the performance assertions made hereinbefore. Actual better engine performance, efficiency and economy, recited also, were factually demonstrable. Repeated tests in vehicles equipped tests in vehicles equipped previously with the patented invention and then with this invention resulted in a general economy of an additional one and one-half miles per gallon of fuel over the fuel saving of the patented invention.

In Fig. 5 there is illustrated a second adapter form of the invention. It is of cup type. Numerals of the one hundred series similar to the primary series indicated in Fig. 5 parts identical or functionally similar to the parts designated by the primary series.

In this form the body portion of the adapter has a peripheral flange 140 projecting outwardly (upwardly and upstream) from the outer edge of groove 144. It may be notched as at 142 to form tongues 141 that frictionally engage the inside wall surface of the intake passage.

This adapter can be pushed upwardly into the outlet end of the down-draft carburetor or downwardly into the intake end of the adjacent intake manifold as desired. It is friction held. The former mounting is preferred because the intake passage junction is then below (downstream of) the insert and vibration if ever effective (as in

a non-notched wall 140 will only cause insert dropping to that junction.

While the invention has been illustrated and described in great detail in the drawing and foregoing description, the same is to be considered as illustrative and not restrictive in character.

The several modifications described herein, as well as others which will readily suggest themselves to persons skilled in this art, all are considered to be within the broad scope of the invention, reference being had to the appended claims.

The invention claimed is:

1. In combination with the valve controlled intake passage of an internal combustion engine, a groove member projecting into said passage from the wall thereof and extending but a slight distance therefrom, the said groove member being downstream of the passage valve and directed upstream for trapping fuel wall condensate, a plurality of ribs projecting into said passage from said groove member, said ribs having upstream directed grooves therein each in communication with the channel of the groove member, and webbing means extending inwardly into the intake from the groove member at the inside edge of said member and at the opposite sides of the intake at right angles to the valve axis and substantially lunar segment-like character and bridging the gaps between certain of the rib members at the ends thereof.

2. A combination as defined by claim 1 wherein the ribs extend across the passage in a general direction transverse to the valve axis and inclined towards each, the closer ends of the ribs being positioned closest to the downstream end of the valve when part open.

3. A combination as defined by claim 1 characterized by the valve being of balanced elliptical type and when approximately quarter open the projected outline thereof being substantially coincident with the inner edges of said webbing means.

4. An insert for inclusion between an engine manifold and a carburetor having substantially aligned matching intake passages and connecting portions, said insert having a passage matching opening therethrough, groove forming means peripherally defining the opening, the groove thereof being directed upstream, the opening defined by said means being but slightly less than that of the matching passage, a plurality of similarly directed rib means extending into the opening from the groove forming means, each rib

means being of groove character and directed upstream and communicating at the groove forming means connected end with the peripheral groove, and webbing means extending inwardly from the inner edge of the groove forming means and connected to the adjacent portions of the grooved rib means at the upper edge thereof, the webbing means being of peripheral discontinuous character and of progressively decreasing width from a central longitudinal plane having the same general direction as the rib means and midway between the relatively most remote rib means.

5. An insert as defined by claim 4 wherein the several openings are circular and all coaxial, and the webbing means is of substantially lunar segment type in outline with an escalloped-like inner edge.

6. An insert as defined by claim 4 wherein the several openings are circular and all coaxial, and the webbing means is of substantially lunar segment type in outline, and the several rib means having inclined direction relative to each other, and toward one portion of the groove forming means, the webbing means being an inward extension of said portion and extending laterally thereof beyond the same, such laterally extending portions being of progressively decreasing radial width.

7. A cup type insert for inclusion in the intake system having a connected manifold and carburetor with matching passages, said insert having a passage matching opening therethrough, groove forming means peripherally defining the opening, the groove thereof being directed upstream, the opening defined by said means being but slightly less than that of the matching passage, a plurality of similarly directed rib means extending into the opening from the groove forming means, each rib means being of groove character and directed upstream and communicating at the groove forming means connected end with the peripheral groove, and webbing means extending inwardly from the inner edge of the groove forming means and connected to the adjacent portions of the grooved rib means at the upper edge thereof, the webbing means being of peripheral discontinuous character and of progressively decreasing width from a central longitudinal plane having the same general direction as the rib means and midway between the relatively most remote rib means, and passage wall friction held upstream directed flange means on the outer edge of the groove forming means.
